(57) **CLAIM**

The ornamental design for a lazy susan with removable pedestal and optional food containers, as shown and described.

DESCRIPTION

FIG. 1 is an isometric view of the lazy susan with removable pedestal, with the central pedestal disposed over the lazy susan handle.

FIG. 2 is an isometric view of the lazy susan with removable pedestal, with the central pedestal removed and disposed above the lazy susan handle.

FIG. 3 is a front elevational view of the lazy susan with removable pedestal, with the central pedestal removed and disposed over the lazy susan handle.

FIG. 4 is a front elevational view of the lazy susan with removable pedestal, with the central pedestal removed and disposed above the lazy susan handle.

FIG. 5 is a rear elevational view of the lazy susan with removable pedestal, with the central pedestal disposed over the lazy susan handle.

FIG. 6 is a rear elevational view of the lazy susan with removable pedestal, with the central pedestal removed and disposed above the lazy susan handle.

FIG. 7 is a right side elevation view of the lazy susan with removable pedestal, with the central pedestal disposed over the lazy susan handle.

FIG. 8 is a right side elevation view of the lazy susan with removable pedestal, with the central pedestal removed and disposed above the lazy susan handle.

FIG. 9 is a left side elevation view of the lazy susan with removable pedestal, with the central pedestal disposed over the lazy susan handle.

FIG. 10 is a left side elevation view of the lazy susan with removable pedestal, with the central pedestal removed and disposed above the lazy susan handle.

FIG. 11 is a front elevational view of the lazy susan with removable pedestal, with the central pedestal disposed over the lazy susan handle; and,

FIG. 12 is a front elevational view of the lazy susan with removable pedestal, with the central pedestal removed and disposed above the lazy susan handle.
